MACHINE FOR FORMING CONTINUOUS
TOBACCO RODS OR FILLERS

Desmond Walter Molins, Deptford, London, England, assignor to Molins Machine Company, Limited, London, England

Application May 3, 1940, Serial No. 333,221
In Great Britain May 10, 1939

10 Claims. (Cl. 131—84)

This invention is for improvements in or relating to machines for forming a continuous tobacco rod or filler, such for example as in continuous rod cigarette making machines or in tobacco packaging machines in which a continuous filler is formed of a larger cross-section than in the previous case.

In prior United States application Serial No. 260,174 there is disclosed apparatus for forming a continuous tobacco filler which comprises a confining passage in which a stream of tobacco is compacted to the cross-section of the passage, a first conveyor wholly external to the passage (e. g. a continuously movable conveyor) to feed a stream of tobacco into the passage, guides, including side guides movable in the same direction as and at substantially the same speed as the conveyor, extending lengthwise of the first conveyor, said guides co-operating with the first conveyor substantially wholly to confine and to compress the stream of tobacco to a cross-section smaller than that of the passage and to control the stream so compressed up to or substantially up to the point at which it enters the confining passage, and a second conveyor movable in the same general direction as and at a linear speed less than that of the first conveyor to move tobacco away from the outlet of the confining passage, the length of said passage being such as to extend on each side of the point of compacting of the tobacco.

It is found that such constructions work in a quite satisfactory manner for long periods of time, but it sometimes happens that an obstruction may occur in the garniture of a cigarette making machine to which such apparatus is applied, the obstruction perhaps being caused by a relatively large piece of stem becoming jammed across the garniture under the tongue and so preventing the regular flow of the tobacco out of the confining passage. In such circumstances since tobacco is still being fed towards the confining passage at a substantially uniform rate there is a tendency for the tobacco in the passage gradually to build up more and more towards the entrance to said passage.

If the obstruction is unduly persistent there will come a time when the building up or packing takes place at a point before the entrance to said passage is reached, that is, packing takes place near the end of the first conveyor. If this should happen there is a tendency for the apparatus to become choked due to the fact that the conveyor runs between side guides which converge rapidly towards the confining passage.

It will be appreciated that if the tobacco is compacting in this manner the tobacco is no longer confined in a passage of substantially constant cross-section and the tobacco tends to spread across the first conveyor and is soon packed into a solid mass. If this choking is not quickly noticed the tobacco conveyor may be broken or otherwise injured, or the pressure of the tobacco due to the jamming may tend to cause the various parts of the mechanism to be dislodged, thus necessitating the re-setting of the apparatus.

By the present invention it is proposed to provide a safety device to minimize the disadvantageous effects due to choking, and this object is achieved by arranging that in apparatus of the kind referred to above the top and side walls (or one of them) of the confining passage can yield under excessive pressure built up by the tobacco when an obstruction occurs and by the provision of guides on that side of the passage from which the tobacco enters the passage, the guides being so arranged as to control the tobacco entering the passage against lateral spreading to an extent such as to enable the entering tobacco to create sufficient pressure in the passage, if a jam occurs, to move the yieldable walls and allow the tobacco to escape. The guides are preferably arranged as plates between the side guides between which the end of the first conveyor runs and arranged in continuation of the upstanding sides of the U formed by said first conveyor band and extending towards the confining passage. The additional guides need not project downwardly so far as to engage the bottom of the first conveyor band, but their depth must be sufficient to ensure that the compressed tobacco stream is adequately guided by them. These additional guides may be arranged to diverge slightly towards the bridge piece.

The top and side walls of the confining passage may be made in one piece which is freely pivoted to supports secured to the bed of the cigarette making machine. If, now, an obstruction is persistent and does not clear itself in time, then the excess of pressure by the tobacco will cause the upper part of the confining passage to turn about its pivot, thus releasing the pressure within the confining passage. When the upper part of the confining passage turns about its pivot the tobacco escapes laterally. The operator is at once made aware of the fact that a jam is occurring and can immediately stop the machine and remove the cause of the obstruction.

It should be understood that the addition of the guides at the inlet side of the confining pas-

age and the yieldable wall or walls of the confining passage are only intended to function as a safety device in case of an obstruction in the garniture. Such obstructions usually occur under the conical tongue piece, and the pressure due to the choke then builds back past the confining passage. The guides according to this invention then control the tobacco sufficiently to prevent it from spreading laterally and to enable it to push open the yieldable wall or walls and so escape. The parts are in all cases so arranged that for normal conditions of operation compacting is effected in a confining passage in accordance with the invention described and claimed in United States application Serial No. 260,174.

The invention will be more fully described with reference to the accompanying drawings, which show a construction generally similar to that shown in Figure 6 of the earlier United States specification referred to above.

In the drawings:

Figure 1 is a side elevation of apparatus for forming a continuous tobacco filler.

Figure 2 is a plan of Figure 1.

Figure 3 is a section of Figure 1 on the line 3—3.

Figure 4 is a section of Figure 1 on the line 4—4.

Parts which are similar in the drawings to those in the specification referred to bear the same references.

Referring to the drawings, tobacco is fed by any suitable tobacco feeding mechanism and is showered so as to be directed downwardly on to the surface of a first conveyor 6 comprising a continuously movable endless band. The shower of tobacco extends along the length of the first conveyor. The tobacco receiving portion of the first conveyor is supported by a stationary rigid member comprising a trough 7 which is so arranged that the endless band 6 is folded by the walls of the trough to substantially U form. The upstanding limbs of the endless band 6 form guides for the stream of tobacco which is formed on the first conveyor by tobacco particles received from the shower of tobacco.

When the tobacco has been received by the first conveyor 6, it is moved thereby away from the hopper or the tobacco feeding mechanism and above the first conveyor there is provided a top guide comprising a shoe 99 with which co-operates a rotatable wheel 91 to ensure that the tobacco passes under the shoe 99.

The shoe and wheel are disposed above the first conveyor at a distance such that a given portion of the tobacco stream on the first conveyor 6 is subjected to a compression which is applied laterally of the direction of movement of the stream by the co-operation of the U shaped first conveyor and the shoe and wheel. Thus the tobacco is subjected to a continuous compression for the purpose of obtaining the necessary rigidity of the tobacco to enable it to enter a confining passage 10, described later, in its compressed state.

The compressed stream of tobacco is fed by the first conveyor 6 and its co-operating moving guides into a confining passage 10 in which the tobacco is compacted in the direction of movement thereof to a cross-section determined by the walls of the confining passage. A second conveyor 11 is provided to move the tobacco from the outlet of the confining passage, and the second conveyor moves at a linear speed which is

less than that at which the first conveyor 6 is moving. In the construction shown, the second conveyor 11 comprises an endless web of cigarette paper which passes over a roller 12 and which is supported by an endless band 13 which latter co-operates with folding mechanism, not shown, arranged to fold the paper web about the continuous tobacco filler supported thereby. Preferably the first conveyor 6 is moved at a sufficiently high speed in relation to the second conveyor 11 that the mass of tobacco on the first conveyor 6 is at all points or substantially all points below the desired mass. When using some modern existing tobacco feeding mechanism it is found that a difference of 20% between the speeds of the first and second conveyors respectively will give the above result. The tobacco feeding mechanism is of course arranged to feed a sufficient quantity of tobacco to form a continuous tobacco filler of the desired mass on the second conveyor.

Since the tobacco carried by the first conveyor 6 is transferred to a slower moving conveyor (i. e. the second conveyor 11), the momentum of the tobacco is reduced. The confining passage 10 through which the tobacco passes is so arranged that the momentum of the tobacco is reduced in the passage and the length of the confining passage is, considered in the direction of movement of the tobacco therethrough, so chosen that the passage extends on either side of the point of compacting of the tobacco, since the point of compacting varies due to the fact that the compressed stream of tobacco fed into the confining passage is at some points of greater mass than at other points.

It will be understood that since the compacting is to be effected in the confining passage 10 after the tobacco has left the first conveyor, it is necessary that the tobacco be given sufficient rigidity to enable compacting to occur in the passage, that is to say, that the tobacco be subjected to a compression which will enable the tobacco to retain its compressed state until it is actually inside the passage before any material lateral expansion occurs. Thus the tobacco is compressed and is controlled in its compressed state up to or substantially up to the confining passage so that it may be said to be pushed into the passage at the faster speed to enable the compacting to be effected inside the passage.

To enable the first conveyor 6 and its co-operating moving guides laterally to compress the stream of tobacco on the first conveyor and control the compressed stream up to or substantially up to the point at which the compressed stream enters the confining passage, the arrangement of the mechanism is such that the roller 14 around which the conveyor 6 passes and the end 15 of the shoe 99 are positioned as closely as possible to the inlet of the confining passage, see Figure 1.

Between the end of the confining passage and the roller 14 there is provided a bridge piece 16 over which the tobacco stream passes from the first conveyor 6 into the inlet of the confining passage 10. A pair of short stationary guides 24 which diverge very slightly towards the bridge 16 are provided to guide the tobacco stream over the bridge 16 as the conveyor 6 flattens out over the roller 14. The length of the bridge piece 16 is reduced to the minimum possible.

In the construction shown, the second conveyor 11 comprises the whole of the bottom wall of the confining passage.

In the construction described above it is found

that there is a considerable amount of heating of the endless band 6 and of the metal parts 7 and 90 with which the band engages. To reduce the heating referred to, water is circulated through apertures formed in the trough 7. As shown in the drawings, cool water enters a passage 25 in the trough 7 through a pipe 26 and passes out of the passage 25 through a pipe 27. A pump, not shown, of any suitable form is provided to circulate the water.

The tobacco stream before being fed into the confining passage is compressed to a cross-sectional size which is smaller than the cross-sectional size of the passage by the co-operation of the first conveyor and guides which extend lengthwise of the first conveyor, and the tobacco so compressed is controlled up to or substantially up to the point at which it enters the confining passage. By reason of the fact that these co-operating guides extend lengthwise of the first conveyor each portion of the tobacco stream will be subjected to a compressing action over a relatively long period of time (that is to say, although the time is only a fraction of a second, it is nevertheless a relatively long time in comparison with the time in which a roller could apply a similar compressive force) and that fact, together with the fact that the first conveyor is wholly external to the confining passage, makes it possible to ensure that the tobacco is compacted at all times under conditions which are the same. This controlled compression gives the tobacco sufficient rigidity to enable it to effect the compacting against the slower moving tobacco moving outwardly from the passage, and makes it possible to ensure that the compacting of the tobacco in the confining passage will, when the machine is operating correctly, take place on the paper web. That is to say, at whatever portion of the passage the tobacco is compacted by a change in speed, the conditions will remain the same, that is, there will be three stationary walls and the bottom wall will be a wall moving at a constant speed.

The description given in the preceding paragraph relates to the normal operation of the apparatus, but as stated in the beginning of the specification, an obstruction in the garniture may occur at times and upset the correct working of the apparatus. For this reason there is provided a safety device consisting of a pair of guides 100 and a pivotally mounted member 101. The top and side walls of the confining passage 10 are constituted by a groove, see Figure 3, in the member 101. This is pivoted at 102 and in severe cases can lift to relieve the pressure on the tobacco. The operator's attention will thus be drawn to the fault in the machine. The guides 100 provide sufficient resistance to lateral spreading of the tobacco on the conveyor 6 in the event of an obstruction causing the tobacco to pack up beyond the entrance of the confining passage, to enable the tobacco to retain a certain amount of rigidity which will be sufficient to apply enough energy to lift the member 101 and so allow the tobacco to escape before it can choke on the conveyor 6 and injure the latter. By keeping the bottom of the guides 100 away from the surface of the band 6, friction is reduced and further, when the member 101 has been lifted in the case of a jam, tobacco can escape below the guides 100 and so tend to reduce the extent to which packing might otherwise occur on the band 6. The machine can continue to run with the tobacco escaping thus without further dam-

aging the machine or any bands, although of course it is not desirable to allow the machine to continue to run in that state.

What I claim as my invention and desire to secure by Letters Patent is:

1. Apparatus for forming a continuous tobacco filler, comprising a confining passage in which a stream of tobacco is compacted to the cross-section of the passage, means wholly external to the passage to feed a stream of tobacco into the passage and arranged substantially wholly to confine and to compress the stream of tobacco to a cross-section smaller than that of the passage, said means retaining said tobacco so compressed substantially up to the point where the tobacco enters the confining passage and means to move the tobacco away from the outlet of the confining passage at a linear speed less than that at which it is fed into the passage, the length of said passage being such as to extend on each side of the point of compacting of the tobacco, said passage comprising stationary top and side walls, the apparatus being so constructed and arranged that at least one of the said walls of the confining passage can yield under excessive pressure built up by the tobacco when an obstruction occurs, and guide elements located on that side of the passage from which the tobacco enters the passage to control the tobacco entering the passage against lateral spreading to an extent such as to enable the entering tobacco to create sufficient pressure in the passage if a jam occurs to move said yieldable wall and allow the tobacco to escape.

2. Apparatus as claimed in claim 1, wherein the said guides form part of the stream feeding means to form a channel of smaller cross-section than the confining passage.

3. Apparatus as claimed in claim 1, wherein the guide elements diverge slightly in the direction of movement of the stream of tobacco.

4. Apparatus as claimed in claim 1, wherein the top and side walls of the passage are made in one piece which is freely pivoted.

5. Apparatus for forming a continuous tobacco filler having a confining passage comprising stationary top and side walls in which a stream of tobacco is compacted to the cross-section of the passage, a first conveyor wholly external to the passage to feed a stream of tobacco into the passage, guides, including side guides movable in the same direction as and at substantially the same speed as the conveyor, extending lengthwise of the first conveyor and co-operating with the first conveyor substantially wholly to confine and to compress the stream of tobacco to a cross-section smaller than that of the passage and to control the stream so compressed substantially up to the point at which it enters the confining passage, a second conveyor movable in the same general direction as and at a linear speed less than that of the first conveyor to move the tobacco away from the outlet of the confining passage, the length of said passage being such as to extend on each side of the point of compacting of the tobacco, at least one of said stationary walls being arranged to yield under excessive pressure built up by the tobacco when an obstruction occurs, and guides located on that side of the passage from which the tobacco enters the passage to control the tobacco entering the passage against lateral spreading to an extent such as to enable the entering tobacco to create sufficient pressure in the passage, if a jam occurs,

to move said yieldable wall and allow the tobacco to escape.

6. Apparatus as claimed in claim 5, wherein a guide is opposed to the surface of the first conveyor and comprises a member having a stationary tobacco engaging surface.

7. Apparatus for forming a continuous tobacco filler, comprising a confining passage in which a stream of tobacco is compacted to the cross-section of the passage, means wholly external to the passage to feed a stream of tobacco into the passage and arranged substantially wholly to confine and to compress the stream of tobacco to a cross-section smaller than that of the passage, and arranged to retain said tobacco so compressed substantially up to the point where the tobacco enters the confining passage, said means including a conveyor having a tobacco receiving surface of substantially U form, and means to move the tobacco away from the outlet of the confining passage at a linear speed less than that at which it is fed into the passage, the length of said passage being such as to extend on each side of the point of compacting of the tobacco, said passage comprising stationary top and side walls, the apparatus being so constructed and arranged that at least one of the said walls of the confining passage can yield under excessive pressure built up by the tobacco when an obstruction occurs, and guide elements located on that side of the passage from which the tobacco enters the passage to control the tobacco entering the passage against lateral spreading to an extent such as to enable the entering tobacco to create sufficient pressure in the passage if a jam occurs to move said yieldable wall and allow the tobacco to escape.

8. Apparatus for forming a continuous tobacco filler, comprising a confining passage in which a stream of tobacco is compacted to the cross-section of the passage, an endless conveyor band wholly external to the passage to feed a stream of tobacco into the passage, means to fold the tobacco receiving surface of the conveyor band to substantially U form, a stationary guide disposed between the upstanding limbs of said U and which extends lengthwise of the conveyor band and co-operates therewith substantially wholly to confine and to compress the stream of tobacco to a cross-section smaller than that of the passage and to control the stream so com-

pressed substantially up to the point at which it enters the confining passage, and a second conveyor movable in the same general direction as and at a linear speed less than that of said conveyor band to move the tobacco away from the outlet of the confining passage, the length of said passage being such as to extend on each side of the point of compacting of the tobacco, said passage comprising stationary top and side walls, the apparatus being so constructed and arranged that at least one of the said walls of the confining passage can yield under excessive pressure built up by the tobacco when an obstruction occurs, and guide elements located on that side of the passage from which the tobacco enters the passage to control the tobacco entering the passage against lateral spreading to an extent such as to enable the entering tobacco to create sufficient pressure in the passage if a jam occurs to move said yieldable wall and allow the tobacco to escape.

9. Apparatus for forming a continuous tobacco filler, as claimed in claim 1, wherein the means to feed a stream of tobacco into the passage comprises a conveyor and wherein the means retaining the tobacco compressed up to the point where the tobacco enters the confining passage extend continuously along a relatively long portion of the conveyor and co-operate with the conveyor substantially to enclose and to subject the tobacco stream thereon to a high compression, and wherein guides having passages formed therein co-act with said means and conveyor, and wherein there is provided circulating means to circulate a cooling fluid through the passages in said guides.

10. Apparatus for forming a continuous tobacco filler, as claimed in claim 1, wherein the means to feed a stream of tobacco into the passage comprises an endless conveyor band and wherein, a guide folds the tobacco receiving surface of the band to U form, and wherein a stationary member having a continuous tobacco engaging surface extends along a relatively long portion of the band and cooperates therewith substantially to enclose and to subject the tobacco stream to a high compression, said guide having a passage formed therein, and wherein circulating means is arranged to circulate a cooling fluid through the passages in said guide.

DESMOND WALTER MOLINS.
